UNITED STATES PATENT OFFICE.

LORNE EMERY KENNEDY, OF RUSSELL, MANITOBA, CANADA.

SCISSORS OR SHEARS.

No. 892,995.

Specification of Letters Patent.

Patented July 14, 1908.

Application filed December 2, 1907. Serial No. 404,692.

To all whom it may concern:

Be it known that I, LORNE EMERY KENNEDY, of the village of Russell, in the Province of Manitoba, Canada, clerk, have invented certain new and useful Improvements in Scissors or Shears, of which the following is the specification.

The invention relates to improvements in scissors, shears, and the like, and the object 10 of the invention is to provide a simple, durable, and inexpensive tension device, which may be adjusted from time to time, to cause the blades to move close together along their entire cutting edge from heel to point, and 15 also to enable the blades to work freely when swung wide open.

It consists essentially in a ball carried by one of the blades and rolling on the other, and a spring and adjusting screw, the parts 20 being arranged and constructed as hereinafter more particularly described.

Figure 1 is a top plan view of a pair of scissors supplied with my invention. Fig. 2 is an enlarged vertical cross sectional view 25 through the heel of the blades, the section being taken in a plane, as denoted by the letters X X', Fig. 1. Fig. 3 is an enlarged vertical cross sectional view, taken through the scissors, at the positions denoted by the 30 line Y Y', Fig. 1. Fig. 4 is an enlarged detailed perspective view of the spring. Fig. 5 is an enlarged detailed perspective view of the ball.

In the drawings like characters of reference indicate corresponding parts in each figure.

1, 2, are blades of any preferred construction in their general outline.

3 is the ordinary screw, forming the pivotal point of the blades.

In one face of the scissors, at the heel, is cut away a portion forming a longitudinal groove 4, slanting from the tips backwardly, and at the rear end of the groove a more or 45 less hemispherical opening 5 is made directly through the heel forming a bearing for the reception of a ball 6, the ball being put in from the upper face of the shear. When the ball is in position it bears on the inner face of 50 the shear 2, and in the movement of the blades, rolls on the lower blade.

7 is an arched spring, of a width and length sufficient to conveniently pass within the groove, the one end resting on the top of 55 the ball, and the other having an opening to

receive the adjusting screw 8, which screws into the heel of the blade 1.

It will be noticed that the bend in the spring and the slant bottom of the groove allows for an adjustment to the outer end 60 pressure of the spring by turning the screw 8. Tightening the screw forces the ball downwardly against the lower blade 2, and the ball being to the other side of the screw from the points, the blades are forced together along their complete cutting edge. According to the adjustment of the screw 8 so the pressure on the blades.

If the heel of the blades in the ordinary scissors be not wide enough to allow the ball 70 to bear on the inner face of the under blade for the complete opening of the scissors when cutting, an additional side extension or lug can be formed at the heel to allow for it as shown at 9 in Fig. 1.

It will be noticed that when the scissors are wide open, that is, further open than is usual in cutting, the ball is free of the heel, so that the blades can work freely. As the ball is free to roll there is considerable less 80 friction than there would be otherwise.

I am aware that a ball has been used between the blades already, but in the form which has come under my notice its value is simply to reduce friction and impart easy 85 motion to the blades. It is not in any manner used as the agency by which the pressure is adjusted between the blades.

What I claim as my invention is:

In a device of the class described the combination with the blades held together by a pivot screw, one of said blades having a longitudinal groove in the heel thereof, the said groove being beyond the pivot screw from the tip of the blades and having an inclined 95 bottom, of a ball within an opening passing from the groove to the under face of the blade, the said ball being adapted to operate on the opposing blade, a spring within the groove having its one end on the ball, and 100 an adjustable screw passing through the other end of the spring into the heel of the blade, as and for the purpose specified.

Signed at Russell, in the Province of Manitoba, this 28th day of October 1907.

LORNE EMERY KENNEDY.

In the presence of—

A. R. TINGLEY,
ADA M. ROGERS.
